[57] **CLAIM**

The ornamental design for a bicycle accessory holder for mounting on a bicycle frame, as shown and described.

DESCRIPTION

FIG. 1 is a top plan view of a bicycle accessory holder for mounting on a bicycle frame showing my new design;

FIG. 2 is a bottom plan view thereof;

FIG. 3 is a right side elevational view thereof, the left side being a mirror image of that shown;

FIG. 4 is a rear end elevational view thereof;

FIG. 5 is a front end elevational view thereof; and,

FIG. 6 is a perspective view thereof.
